Inventor

UNITED STATES PATENT OFFICE

EMILY OAKLEY, OF LOS ANGELES, CALIFORNIA

RUBBER BASE FOR TELEPHONES AND THE LIKE

Application filed January 30, 1931. Serial No. 512,273.

My invention relates to bases for telephones and similar devices and has particular reference to a base formed of rubber or similar composition to be employed in connection with hand telephones of the type in common use and known in the art as desk telephones.

In connection with objects formed of metal to be placed upon the smooth surfaces of such tops of desks, considerable difficulty has been encountered in the past due to these metal objects injuring the finish of the surface upon which they are placed. This is particularly true in connection with desk telephones in which the metal bases of the telephones are placed upon the surfaces of desks, tables and similar articles of furniture with the result that unless the bases are covered with some non-metallic material injury to the finish of the desks occurs. Also, telephones of the dial selecting type, when used on desks, are readily moved under the influence of the movements of dialing or selecting the station to be called, rendering it awkward to properly operate the selecting dial of the telephone. Heretofore, covers for the bases of such telephones were formed of cloth or felt, or similar material, which, to some extent, avoided injury to the surface of the desks and the like, but did not eliminate the movement of the telephone during manipulation of the dial.

It is, therefore, an object of my invention to provide a base for metal articles, such as telephones, which will have both the character of preventing injury to surfaces upon which such objects may be placed, and also to have the property of increasing the frictional contact between the object and the surface upon which it is placed.

Another object of the invention is to provide a base for objects, such as telephones, in which the base is formed of suitable surface gripping material, such as pliable rubber.

Another object of the invention is to provide bases for telephones and the like in which a relatively thin sheet of pliable rubber may be attached to the metal base of the telephone to insure against contact of the

metal with the surface upon which it may be placed.

Another object of the invention is to provide a pliable rubber base for a telephone which may be so formed as to be readily attachable to the metal base of the telephone.

Another object of the invention is to provide a pliable rubber base for a telephone in which the base may be attached to the telephone by inserting the same between the metal base and the superstructure of the telephone, thus securing the edges of such rubber base within the metal assembly of the telephone.

Other objects of my invention will appear from a study of the following specification, read in connection with the accompanying drawing, in which

Figure 1 is a front elevational view of a portion of a desk type telephone illustrated partly in section, showing my rubber base in place thereon.

Figure 2 is a detail sectional view of the rubber base per se illustrating in detail the construction thereof, the section being taken along line II—II of Figure 3.

Figure 3 is a plan view of the rubber base per se illustrated in Fig. 1.

Figure 4 is a detail plan view showing the underneath side of the rubber base illustrated in Fig. 3.

Figure 5 is a sectional view similar to that shown in Fig. 1, and illustrating a modified form of my telephone base assembly upon the metal base of a telephone.

Figure 6 is a detail sectional view illustrating a still further modified form of my rubber base as applied to the metal base of a telephone.

Figure 7 is a detail plan view of the underneath surface of the metal telephone base, to which the form of rubber base illustrated in Figure 5 may be attached.

Referring to the drawing, I have illustrated in Figure 1, a telephone stand comprising a tubular upright 1 to which the transmitter and receiver of the telephone (not shown) may be attached. The tubular upright 1 is rigidly secured in any suitable manner to an inverted cup-like support 2 normally

employed for housing the internal housing of the telephone and constituting the support for a dialing structure such as is in common use in desk telephones.

A cover or base 3 formed of metal is usually provided for attachment to the underneath side of the support 2 as by means of screws 4 which extend through depressions 5, one or more of which are formed in the metal base to coincide with the projecting legs or feet 6 of the attaching bracket 7 secured in a suitable manner to the support 2 and upright 1. The metal base 3 is usually formed with an upstanding flange 8 which coincides with the downwardly depending wall 9 or flange 9 of the support 2 so as to make a relatively tight joint therewith.

The construction hereinbefore described is substantially that of the construction of the metal parts of the ordinary telephone, the flange 8 being provided with either an inwardly and upwardly projecting shoulder to fit within the depending flange 9 of the support 2, or in some instances a separate ring of metal is inserted within the flange 8 to extend upwardly into engagement with the inner wall of the flange 9.

The construction as herein described and as now used in connection with telephones, is such that a felt or cloth covering placed upon the underneath side of the plate 3 and drawn inwardly to be clamped between the flange 8 and the depending flange 9 insures the covering of the metal parts of the telephone which will contact with the desk surface or other surface upon which the telephone may be placed. However, the felt surface or cloth surface is unable to grip the desk surface sufficiently to prevent ready displacement of the telephone due to any manipulation of the telephone parts for example the manipulation of the dial in selecting the telephone station desired.

By referring to Fig. 1, it will be observed that I have provided a cover or exterior base 11 preferably formed of resilient material having a high frictional coefficient. For example, this material may be live rubber which I prefer to form of substantially pure rubber, vulcanized only to such degree as will provide a soft pliable elastic rubber composition.

The rubber base 11 is preferably formed with a plurality of corrugations 12 upon its underneath side, these corrugations being illustrated in Fig. 4 as comprising a series of concentric circular projections. Although it is to be understood that any other configuration may be given to the corrugations or outer standing flanges 12 in order to increase the frictional grip which the base will attain upon any surface upon which it is placed.

Referring particularly to Fig. 3, it will be observed that the rubber base 11 is formed with a substantially flat circular surface 13,

bordered by an upstanding flange 14, the diameter of the base 11 being preferably somewhat smaller than the diameter of the metal base 3 upon which it is to be placed so that when in place the natural resilience of the rubber material will tend to fit the rubber base snugly upon the metal surface.

Referring particularly to Fig. 2, it will be observed that the upstanding flange 14 on the base 11 is provided with an inwardly projecting lip 15, and terminates in a downwardly depending flange 16 formed integrally with an upstanding flange 17, the flanges 16 and 17 constituting in effect an annular ring of the base material which will engage between itself and the flange 14 the upstanding flange 8 of the metal base when in place thereon. The flange 14 and the inwardly projecting portion 15 are preferably connected to the circular base surface 13 by means of curved connecting portions 18 and 19, to insure substantially constant thickness of material throughout the base construction and to avoid sharp corners which might constitute points of weakness in which splitting of the material might occur.

The upstanding lip 17 will extend upwardly into engagement with the inner wall of the depending flange 9 of the support 2 when the base is in place upon the telephone structure so that the lip 17 will constitute a guide for the flange 9 and will insure sufficient material upon the interior of the support 2 to prevent withdrawal or displacement of the rubber base when the base is in use.

By referring again to Fig. 3, it will be observed that the circular flat portion of the base is formed with a plurality of depressions 20 formed upon the inner surface thereof, the number and location of such depressions corresponding to the various types of supports 7 which may be employed upon various types of telephone stands to which my base is adapted. That is, in certain types of telephones now in use, the support 7 is constituted by a bracket having three feet depending therefrom spaced equidistant above a center 21, these depressions being indicated specifically by the reference character 20a.

Another type of telephone stand is provided with a three footed bracket in which all of the feet are in alignment with each other, the depressions corresponding to this type of telephone being specifically indicated by the reference character 20b.

A still further type of telephone employs a two footed bracket, the location of the feet corresponding to the depressions specifically indicated by the reference character 20c.

By forming my telephone base with the plurality of depressions spaced as indicated, a single base is adapted to enter all of these various types of telephones. Thus by punching out or cutting out the material lying within the depressions 20 to correspond

with the particular type of telephone with which the base is to be used, the necessary openings through the rubber base for manipulation of attaching screws 4 may be readily formed.

5 It will be observed that with the construction hereinbefore described in place upon the metal base 3 of the telephone which is then attached to the support 2, a non-metallic cover is placed over the telephone base to 10 insure against marring of the surface upon which the telephone may be placed, while at the same time the gripping surfaces of the live rubber or similar material of which my base is constructed will insure sufficient gripping of the telephone to prevent this movement during dialing or accidental touching of the telephone.

15 It will also be observed that due to the fact that my rubber or similar material base is 20 constructed of smaller diameter than the metal base of the telephone, a flat surface is always presented upon the underneath side of my base, even though the metal base of the telephone may be depressed at certain 25 points, as is indicated at 5.

If desired, however, my base may be 30 formed as is indicated in Figs. 5, 6 and 7 with a cross sectional configuration corresponding to the configuration of the depression 5 of the metal base 3 so that even at such points as the metal base may be depressed a flat surface contact is obtained between the rubber base 35 11 and the metal base 3.

While I have illustrated and described the telephone base as being formed as a separate part which may be readily attached to the telephone and detached therefrom, my device 40 may be constructed integrally with the metal base of the telephone as by vulcanizing the rubber or similar material of which the base is formed directly to the metal base of the telephone. Such modification of my device 45 is illustrated in Figs. 6 and 7 in which the metal base 3a, constituting the metal base of the telephone, may be formed with a plurality of corrugations 23 preferably formed as concentric circular flanges formed upon 50 the underneath side of the base 3a to present a corrugated or roughened surface thereon to which live rubber may be attached to form the base 11 of the telephone.

It will be apparent that when vulcanizing 55 the rubber or similar material in place, an integral structure is formed which may be placed upon the support 2 and attached thereto.

While I have illustrated and described the 60 preferred embodiment of my invention, I do not desire to be limited to any of the details shown or described herein, except as defined in the appended claims.

I claim:

65 1. An anti-slipping cover for the base of

telephones including a rubber pad integral throughout and formed to extend over the bottom of the telephone base when in use, said pad having an upstanding wall provided with an inturned annular lip at the upper 70 edge and a retaining annular ring of rubber integral with the base, said ring of rubber extending on the opposite sides of said lip and parallel with said flange but spaced inwardly from the flange.

75 2. An anti-slipping cover for the base of telephones including a rubber pad integral throughout and formed to extend over the bottom of the telephone base when in use, said pad having an upstanding wall provided 80 with an inturned annular lip at the upper edge and a retaining annular ring of rubber integral with the base, said ring of rubber extending parallel with said flange but spaced inwardly from the flange.

85 3. An anti-slipping cover for the base of telephones including a rubber pad integral throughout and formed to extend over the bottom of the telephone base when in use, said pad having an upstanding wall provided 90 with an inturned annular lip at the upper edge, and an upstanding guide flange formed on the inner edge of said lip and extending parallel with said first named flange but spaced inwardly therefrom to guide the 95 telephone support into position on said base.

Signed at Los Angeles, California, this 21st day of January, 1931.
